UNITED STATES PATENT OFFICE.

WILLIAM R. DEMAREST AND HENRI VAN HERCK, OF NEW HAVEN,
CONNECTICUT, ASSIGNEES TO AARON T. DEMAREST, OF NEW
YORK, N. Y.

DESIGN FOR A COACH-LAMP.

SPECIFICATION forming part of Design No. 21,672, dated June 28, 1892.

Application filed May 31, 1892. Serial No. 435,075. Term of patent 3½ years.

To all whom it may concern:

Be it known that we, WILLIAM R. DEMAREST and HENRI VAN HERCK, of New Haven, in the county of New Haven and State of Connecticut, have invented a new Design for a Coach-Lamp; and we do hereby declare the following, when taken in connection with accompanying drawing, to be a full, clear, and exact description of the same, and which said drawing constitutes part of this specification, and represents a face view.

This invention relates to a design for coach-lamps; and the design consists in the shape or configuration of the parts, as shown in the accompanying illustration. The body of the lamp is substantially square horizontally, the lights or panels present a horizontal line at the top, the sides running down parallel, the bottom semicircular, and the bottom of the

panels merging into the spherical shape of the body of the lamp. From the bottom the candle-holder extends downward, as usual. The crown of the lamp represents a hemispherical dome shape at the top, and from the base of the crown leaf-like ornaments spring outward and curve inward and upward and again outward around the lower edge of the dome, as shown in the accompanying illustration.

We claim—

The design for a coach-lamp, as herein shown and described.

In testimony whereof we have signed this specification in the presence of two subscribing witnesses.

WILLIAM R. DEMAREST.
HENRI VAN HERCK.

Witnesses:

FRED. C. EARLE,
GEORGE D. SEYMOUR.
